UNITED STATES PATENT OFFICE.

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK.

BELT-BUCKLE.

1,374,611.

Specification of Letters Patent. Patented Apr. 12, 1921.

Application filed September 9, 1920. Serial No. 409,103.

To all whom it may concern:

Be it known that I, LOWELL W. SHIELDS, a citizen of the United States, and resident of Rochester, in the county of Monroe and 5 State of New York, have invented certain new and useful Improvements in Belt-Buckles, of which the following is a specification.

The present invention relates to belt 10 buckles and more particularly to the type in which a buckle frame is provided formed with side flanges having inwardly extending portions for confining the belt end, combined with a clamping member which will 15 clamp the belt end under such inwardly extending portions, an object of this invention being to provide a novel means for mounting the clamping means on the side flanges so that a maximum space may be 20 provided between the pivot of the clamping member and the front plate of the buckle while at the same time permitting the mounting of the pivot pin in the side flanges without increasing the distance between the 25 inwardly turned portions and the front plate of the buckle.

To these and other ends the invention consists of certain parts and combinations of parts, all of which will be hereinafter 30 described, the novel features being pointed out in the appended claim.

In the drawings:

Figure 1 is a front view of a buckle constructed in accordance with this invention;

Fig. 2 is a side view of the buckle;

Fig. 3 is a rear face view;

Fig. 4 is an end view;

Fig. 5 is a fragmentary section showing the clamping member in unclamped position;

Fig. 6 is a fragmentary view showing the clamping member in clamped position;

Fig. 7 is a fragmentary view of one end of the buckle frame showing the clamping member removed; and

Fig. 8 is a detail view of the clamping member.

In the manufacture of belt buckles of the type heretofore mentioned, difficulty has 50 been experienced in mounting the pivoted clamping member at the proper distance from the front plate so as to accommodate thick straps without making a buckle of such a width as to cause the buckle to ap-

pear bulky or without arranging the pivotal 55 clamping member in such a position that it appears conspicuous from its flange side. According to this invention it is possible to reduce the width of the sides to a minimum while at the same time the pivoted 60 clamping member has its axis of turning located at such a distance from the front plate that a thick belt may be held without making the clamping member conspicuous 65 from the sides.

Referring to the embodiment of the invention herein illustrated, 1 indicates the front plate of the buckle frame which has side flanges 2 formed with inwardly turned projections or portions 3. The front plate 70 is curved or bulged at its center while the inwardly turned projections or portions 3 are substantially straight, so that, at the center of the buckle, the distance between the inwardly turned portions and the front 75 plate is greater than at the ends of said inwardly turned portions, thus facilitating the passage of the strap end between the front plate and the overhanging projections 3.

In order to provide for the pivotal mounting of the clamping member 4, the side flanges 2 are provided beyond one end of each of the inwardly turned portions 3 with projections 5 which extend in rear of the inwardly projecting portions 3. These extensions are formed with inwardly turned arched or curved flanges 6. A pivot pin 7 connects the projections 5 and on this pivot pin the clamp 4 turns, this clamp being preferably formed from a single piece of 90 sheet metal bent to provide a clamping portion 4^a and a strap securing portion 4^b which is perforated or cut to provide an opening 4^c to which the belt end 8 is secured. The clamping member also has ears 4^d at opposite ends of the clamping portion 4^a bent upwardly and perforated. Through these perforations the pivot pin 7 extends. The sides of these perforations abut the arched or curved flanges 6 on the projections 5 and 95 limit the longitudinal movement of the clamping member on the pivot pin 7.

From the foregoing it will be seen that the pivot of the clamping member is arranged at such a distance from the rear face 105 of the front plate that it is possible to clamp a belt end of maximum thickness and this without increasing the width of the side.

flanges or rendering the buckle conspicuous from the side.

What I claim as my invention and desire to secure by Letters Patent is:

5 A belt buckle comprising a front plate, side flanges having inwardly turned portions and also portions extending rearwardly beyond said inwardly turned portions at one end of each of said inwardly

turned portions, said rearwardly extending portions having arch shaped inwardly turned flanges, the ends of the latter nearest the side flanges merging into said side flanges, a pivot pin connecting said rearwardly extending portions, and a pivoted clamp supported on said pin and abutting said arch shaped inwardly turned flanges.

LOWELL W. SHIELDS.
